(57) **CLAIM**

The ornamental design for a stand for sign, as shown and described.

DESCRIPTION

FIG. 1 is a top and front perspective view of a stand for a sign, showing our new design;

FIG. 2 is a top and rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

In the drawings, the broken lines depict portions of the stand for sign forming no part of the claimed design. The dash-dot broken lines define the bounds of the claimed design and form no part thereof.
